BALLAST WATER RECOVERY FOR
AIRSHIPS

Wilhelm O. L. Fischer, Akron, Ohio, assignor to
Goodyear-Zeppelin Corporation, Akron, Ohio,
a corporation of Delaware

Application January 27, 1934, Serial No. 708,596

6 Claims. (Cl. 244—61)

This invention relates to airships and particularly to airships which are inflated with helium and hydrogen or exclusively with hydrogen as a lifting gas and has for its object the improvement of airship efficiency.

The lifting power of an airship on the ground is greatest when the gas cells are fully inflated at atmospheric pressure. Airships operated with hydrogen usually are completely or hundred per 10 cent inflated at the take-off and because of its relatively low cost, the gas when expanded at higher altitudes and lower air pressure is simply discharged into the atmosphere. Helium airships, on the other hand, are inflated only to a 15 certain percentage of their gas cell capacity to permit the expensive helium to expand within the cells rather than be discharged. This incomplete inflation, of course, reduces the lifting power perceptibly. To this lift reduction must be added 20 the lower lifting power of helium, which is approximately ten per cent below that of hydrogen. However, helium has the great advantage of being non-inflammable and therefore is preferred as a lifting gas.

It has been proposed to improve the efficiency 25 of helium-inflated airships by adding gas cells inflated with hydrogen which are protected by the surrounding helium. This procedure makes it possible to fully inflate the gas cells and to valve off the cheaper hydrogen instead of the expensive 30 helium when the gases expand. In order to keep the ship in trim it has moreover been necessary in most prior airships to discharge some of the gas to compensate for the weight of liquid fuel consumed by the internal combustion engines 35 used to propel the airship. The discharged gas, of course, is lost. Instead of simply discharging the hydrogen, attempts have been made to burn it either alone or together with liquid fuel in an 40 internal combustion engine. However, these attempts have not given satisfactory results, because suitable engines for that purpose are not available.

Another method for keeping the buoyancy of 45 the airship constant as much as possible has been successfully applied in helium-inflated airships by recovering the water contained in the exhaust gases discharged from the internal combustion engines, which furnish the propelling power. 50 Under favorable conditions sufficient water can be recovered to compensate for the weight of fuel and oil consumed. However, the condensers, for cooling the water vapor contained in the exhaust gases down to the dew point, must be very large 55 and are accordingly heavy. Another drawback of this system is the fact that the water recovered contains admixtures of soot, oil, sulphur and other impurities, which make it impossible to use the water for washing, drinking, cooking, etc. The 60 impurities also deposit on the condenser walls

decreasing the heat dissipation through the walls and the gases further tend to attack and destroy the metal of the condensers by corrosion in a relatively short time.

The present invention is a decided improvement 5 over known methods of keeping an airship in proper buoyancy and relies on a new and novel water recovery system. It avoids and overcomes the imperfect and objectionable features of former methods of recovering water from propelling motor exhaust gases and also accomplishes the recovery of a greater amount of actually pure water with a much smaller condenser system which weighs considerably less.

Instead of recovering the combustion product 15 of the hydrogen contained in the liquid fuel which is burned in the internal combustion engines, it is proposed to burn hydrogen, carried in separate, relatively small bags surrounded by uninflammable helium, underneath a steam boiler, which 20 furnishes the steam to one or more steam engines, preferably turbines. These turbines furnish additional power for propelling the ship in conjunction with the usual internal combustion engines operated by gasoline or oil. The combustion product obtained by this new method consists 25 only of water vapor which is mixed with the nitrogen of the combustion air. The resulting condensate is very pure water. One pound of the boiler flue gases contains about three times as 30 much water as one pound of the exhaust gases from the ordinary internal combustion engines. This is because the exhaust gases from the ordinary internal combustion engine include considerable quantities of carbon dioxide and other 35 gases having little or no water content. The combustion products of the hydrogen are on the other hand substantially all water.

Due to the fact that the hydrogen gas is completely burned and its water combustion product 40 is recovered, a relatively small volume of hydrogen will be required for compensating the weight of the liquid fuel consumed by the internal combustion engines. The water recovered from the flue gases of the burnt hydrogen will be fully 45 sufficient for compensating the weight of the liquid fuel without resorting to recovering the water contained in the liquid fuel engine exhaust gases. The condenser surface can also be very 50 much smaller whereby the water recovery system is considerably simplified and its weight greatly reduced with a resulting lowering of cost.

Because the water recovered is almost perfectly pure, the fresh water supply to be carried on the ship can be much reduced and payable load 55 carried instead. A soot separator is dispensed with and the condenser is always in clean condition. Another advantage is the uniform and even flow of the flue gases through the condenser avoiding the pulsation of the exhaust from the 60

internal combustion engines which fatigue and shorten the life of the material forming the condenser.

For a better understanding of this invention 5 reference may be had to the accompanying drawing, wherein.

Fig. 1 shows diagrammatically a side view of 10 an airship with the covering partly removed to better illustrate the invention;

10 Fig. 2 shows a front view of the airship.

Referring to the drawing, Fig. 1 illustrates an 15 airship 5 which is equipped with a liquid fuel supply 1 for feeding the internal combustion power units 9 which provide the main propelling power for the airship. The interior space 12 of the airship 5 is usually divided up into a number 20 of compartments which contain the lifting gas, either helium or hydrogen generally enclosed in individual gas cells (not shown). In case helium is used as main lifting gas, relatively small gas cells 13 containing the inflammable hydrogen are disposed within the non-inflammable helium.

The hydrogen of course serves as lifting gas 25 during flight but it can, as desired, be fed as fuel by a pipe line 14 to a steam generator 15 where it is burnt to change the water in the generator to steam. A pipe line 16 leads the generated steam to a steam engine 17, preferably of the 30 turbine type, which furnishes additional propelling power. The exhaust of the steam engine passes through a pipe line 18 into a condenser 19 from where it is returned in condensed state into the steam generator by a conduit 20.

The flue gases formed by the hydrogen burnt 35 at the steam generator 15 are conducted by a pipe line 21 into a second condenser 22 from which the condensate, pure water, is drained by a pipe line 23 into a ballast container 24. Through outlet 25 the nitrogen and other unburnt gases from the 40 combustion air escape into the atmosphere. It will be appreciated that the hydrogen is burnt at such times and in such quantity as to compensate for the liquid fuel used by the regular internal combustion engines. The recovered water can be 45 used for drinking, cooking and the like as it is very pure. Since the exhaust steam from the turbines carries few if any impurities, the invention contemplates under certain conditions if desired combining the condenser for the exhaust 50 steam and the condenser for the flue gases into a single unit.

From the foregoing description, it will be apparent that I have devised a very efficient and most simple method for automatically obtaining 55 pure ballast water. While I have shown only one form my invention may assume it will be apparent to those skilled in the art that it is not so limited but that various modifications and changes may be made therein without departing 60 from the spirit of my invention or from the scope of the appended claims.

What I claim is:

1. In combination with an airship, lifting-gas 65 compartments containing helium, at least one lifting-gas compartment containing hydrogen, the hydrogen compartments being surrounded by helium, means containing liquid fuel, a steam power plant including an external combustion motor for burning some of said hydrogen exclusively without contamination, an internal combustion power plant operated by the liquid fuel, a condenser for condensing the water vapor formed by the burning of the hydrogen, water containers for storing the condensed water, and a second

condenser for condensing the exhaust steam from the steam power plant, said steam and internal combustion power plants being so proportioned to each other that the amount of condensate collected will substantially equal in weight the amount of liquid fuel used, minus the amount of lift of the gaseous fuel burned. 5

2. In combination with an airship, lifting-gas compartments containing helium, lifting-gas compartments containing hydrogen, the hydrogen compartments being surrounded by helium, an external combustion power plant using hydrogen lifting gas exclusively for fuel, a condenser system for condensing the combustion product of the hydrogen into water fit for human consumption, and water containers for storing the recovered water to thereby keep the ship in trim and to offset the use of ballast, drinking, cooking or like water, and taking into account any loss of lifting effect of the gas. 10

3. In combination with an airship, of lifting-gas compartments containing helium, lifting-gas compartments containing hydrogen, the hydrogen compartments being surrounded by helium, means containing liquid fuel, an external 15 combustion power plant using said hydrogen exclusively for fuel, an internal combustion power plant operated by the liquid fuel, a condenser system for condensing the combustion product of the hydrogen into water fit for human consumption, and water containers for storing the recovered water to thereby keep the ship in trim and to offset use of ballast, drinking, cooking, 20 washing or like water, and taking into account any loss of lifting effect of the lifting gases in 25 the ship. 30

4. The combination with an airship using a combustible gas, at least in part, for lifting said airship, of an external combustion motor plant on said airship for burning said combustible gas 40 which, when burned, is substantially entirely reduced to water fit for human consumption, an internal combustion power plant using liquid fuel, and a ballast water recovery system for condensing the product of combustion of the gaseous 45 fuel into water and storing the recovered water on said airship to thereby maintain the balance of the airship by compensating for loss of the liquid fuel as it is used. 50

5. That method of maintaining substantially 55 constant the buoyancy of a lighter-than-air aircraft, using a combustible gaseous fuel at least in part for lifting, which comprises employing external and internal combustion motors on the aircraft for propulsion purposes, using liquid fuel for the internal combustion motor, using some of said combustible lifting gas for fuel in the external combustion engine, the gaseous fuel being one which when burned is substantially entirely reduced to water, and condensing and storing the 60 water so formed to compensate for loss of fuel burned in the internal combustion motor. 55

6. The method of supplying an airship, using 65 a burnable water producing lifting gas at least in part, with water fit for human consumption, comprising the steps of burning at least part of said gas in an external combustion power plant on said airship out of contact with matter which would contaminate same to an extent which would render it unfit for the purpose set forth, condensing the water vapor formed by said burning, and utilizing the energy developed in 70 said power plant for airship operations. 70
